HIGH FREQUENCY ELECTRON DISCHARGE DEVICE

Bernard Salzberg, East Orange, N. J., assignor to
Radio Corporation of America, a corporation of
Delaware

Application November 30, 1939, Serial No. 306,781

7 Claims. (Cl. 250—27.5)

My invention relates to electron discharge devices, more particularly to such devices and associated circuits suitable for use at high frequencies.

When conventional electron discharge devices, such as radio tubes, are used at high frequencies the input loading increases as the operating frequency increases. This loss in the input circuit of the tube is the result of the increase of the input conductance and is due to a major extent to the cathode lead inductance, because this cathode lead inductance is common to the plate and grid return circuits.

It is now generally known that the inductance of the cathode lead of an amplifier or converter tube, which is common to both plate and control grid circuits, represents a degenerative coupling between these circuits. This degeneration exhibits itself, when ordinary tubes are used, as a resistance which appears in shunt with the input terminals of the tube and which decreases as the frequency increases. The common cathode lead inductance may be due to the length of the internal cathode lead, or to the length of the connecting wire, or to both. The effective input conductance is, to a first approximation, directly proportional to this inductance. It also depends to a first approximation on the square of the operating frequency and on the cathode transconductance of the tube. The cathode transconductance is equal to the sum of the tube transconductance and the product of the tube transconductance by the ratio of the screen grid to plate current. This form of input loading probably accounts for a considerable portion, if not actually the major portion of the input loading in many commercial tubes.

It is, therefore, the principal object of my invention to provide an electron discharge device and associated circuit in which loading effects, due to the cathode lead inductance, are eliminated or substantially reduced.

The novel features which I believe to be characteristic of my invention are set forth with particularity in the appended claims but the invention itself will best be understood by reference to the following description taken in connection with the accompanying drawings in which Figure 1 is a tube and circuit diagram illustrating the problem solved by my invention, Figure 2 is a diagrammatic representation of a tube and circuit made according to my invention, Figure 3 shows a tube diagrammatically represented and its associated circuit made in accordance with my invention, Figure 4 is a longitudinal section 55

of a modification of a tube and its associated circuit made according to my invention, Figure 5 is a longitudinal section of another form of electron discharge device made according to my invention and Figure 6 is a transverse section along line 6—6 of Figure 5.

In Figure 1 is shown the schematic arrangement of a typical amplifier stage. In this figure the tube is provided with a cathode 10, preferably indirectly heated (heater not shown) control grid 11, screen grid 12, suppressor grid 13 and anode or plate 14. The input circuit 15 is connected between the grid 11 and the cathode 10, the cathode being coupled to the secondary of the input circuit by coupling condenser C₁. The output circuit 16 is connected between plate 14 and the usual voltage supply source 17, the bypassing condensers C₃ and C₂ being used between plate, screen and cathode, the voltage source 17 supplying the usual voltages for biasing the control grid and screen grid. The common cathode lead inductance is represented by an inductance L and may be either due to the length of the internal cathode tube lead, or to the length of connecting wire, or to both. It is because of the inductance of this lead and connecting wire that the degenerative action exhibits itself.

In accordance with my invention one way of solving the difficulties presented is by means of the circuit arrangement and tube shown in Figure 2. Here the tube is provided with two separate leads, the inductances of which are represented by L₁ and L₂. Two A. C. return paths are indicated at I and II. In the arrangement shown the two leads are provided, one for the plate and screen-grid return, and the other for the control-grid return. If the mutual inductance between these two leads is negligible, the common cathode impedance is substantially eliminated and the input loading due to this cause will be practically non-existent. However, if tubes provided with two cathode leads are used in practical amplifier or converter stages, the input loading would not necessarily be greatly improved. The reason is that if the impedance of the path II is small as compared with the impedance of path I, as it may be in an actual circuit, most of the A. C. plate and screen grid return current will flow through path II and hence the lead for the grid return. If it does so, then the object of the two leads is not fully realized for the first cathode lead again constitutes a common inductance. With my invention, however, this difficulty is removed by inserting choke coils or resistors as indicated at 19, 20, 21 and 22. In this way the

A. C. return current is prevented from flowing through the path 11 to the cathode lead L₁ and is forced to flow through the separate return lead L₂. The impedances 21 and 22 can be used alone or the impedances 19 and 20 used alone. These additional circuit elements present a high impedance to the return currents of the operating radio frequencies and preferably though not necessarily a low impedance to the D. C. return currents.

The operation of the tube can be still further improved by connecting the by-passing condenser 18 directly to the cathode as shown in Figure 3 at 18'.

In one successful example of my invention in which the screen grid lead was by-passed to the control grid-cathode return lead the impedance 21 was a 60,000 ohm resistor and impedance 22 a 5,000 ohm resistor, the by-pass condensers were all of a value .002 mfd. With this arrangement I measured an input conductance of about 130 μ mhos at 60 mc. as compared to 500 μ mhos in a conventional tube for the same value of plate current. The improvement was therefore, of a ratio of 4 to 1.

Carrying the above teaching further, the cathode may be provided with as many leads as there are electrodes in addition to the cathode. These leads can then be each separately connected as shown in Figure 2 by means of by-pass condensers to one of the other electrodes using suitable chokes or resistors to keep the radio frequency currents out of common paths due to common leads.

However still further improvement can be obtained. The A. C. screen grid current in the arrangement above still flows through the first or control grid cathode lead, and since the ratio of the screen grid to cathode current was about 1 to 5 in the tube tested, the degenerative effect of the screen grid current gave rise to an input conductance of about 100 μ mhos. This would leave roughly 30 μ mhos for the input conductance of the tube if the degenerative effect of the screen grid current could be eliminated. The over-all improvement might then be of the order of 16 to 1 under these conditions.

A tube in which this improvement can be obtained is shown in Figure 3 in which the tube is provided with two cathode leads and an internal by-pass capacitor connected inside the envelope directly between the screen grid and cathode. The object of this by-pass capacitor is to prevent the effect of the screen grid impedance by connecting this electrode for A. C. directly to the cathode within the tube. This eliminates the degenerative effect of the screen grid current and insures better shielding at high frequencies. The capacitors can be of two types; namely, commercial capacitors mounted on the tube structure, or built-up capacitors which make use of mica spacers at each end of the tube. This last arrangement is shown in Figure 4.

Here the cathode 10, control grid 11, screen grid 12, suppressor 13 and anode 14 are mounted coaxially and in the order named between a pair of mica spacer members 25 and 25'. Alternate metal plates 28, 31, 34 and micas 30 and 33 at the bottom of the mount provide the by-passing condensers required for the purposes set forth above. It will be noted that the screen grid 12 is connected by means of connector 29 to the metal plate 28. The cathode is connected to the metal plate 31 by connector 32 and the

suppressor grid to the metal plate 35, so that in effect a by-pass condenser is connected between the cathode and screen and between the cathode and suppressor which last grid may be maintained at a potential less than that of the screen and higher than that of the cathode through the impedance 13'. This arrangement of by-passing condensers can be duplicated at the top of the mount by means of the alternate metal and mica plates 28', 31', 34', 30', and 33', the connections being made by connectors 29', 32' and 35'. The cathode is again provided with two leads 26 and 27. The impedances 19', 20', 21' and 22', as well as 13', being shown as resistors instead of inductances as shown in Figure 2. It is understood that impedances 21' and 22' can be used without impedances 19' and 20', and that impedances 19' and 20' can be used without 21' and 22' if desired.

A modification of the arrangement shown in Figure 4 is shown in Figure 5. The metal plate 45 is a complete disc and is electrically connected to cathode 10 by connector 46. The plates connected to the screen and suppressor grids however are half discs as best shown in Figure 6, half disc 40 or segment 40 being connected by the electrical connection 41 to the suppressor grid and the disc 42 to the screen grid by means of connector 43, these metal plates being electrically insulated from each other by mica spacer 44. This arrangement could of course be duplicated at the top of the mount.

The degenerative effect of the A. C. screen grid current can be still further reduced by using tubes designed to have a low screen grid current. It is now generally known that such tubes also possess the virtues of reduced fluctuation noise and increased efficiency.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device having an envelope containing a cathode and an anode, and a plurality of grids positioned between the cathode and anode and including a signal grid, screen grid and suppressor grid, said cathode having a plurality of leads extending between the cathode and the exterior of the envelope, mica spacers at opposite ends of the mount for spacing the cathode, anode and grids, an additional mica spacer and a conducting plate on each side of said additional mica spacer all adjacent one end of said mount, one of said conducting plates being electrically connected to the screen grid and another of said plates being electrically connected to the cathode.

2. An electron discharge device having an envelope containing a cathode and an anode, and a plurality of grids positioned between the cathode and anode and including a signal grid, screen grid and suppressor grid, mica spacers at opposite ends of the mount for spacing the cathode, anode and grids, alternate mica spacers and conducting plates being adjacent each end of said mount, one of the conducting plates at each end of the mount being electrically con-

nected to the screen grid and another of said plates at each end of the mount being electrically connected to the cathode.

3. An electron discharge device having an envelope containing a cathode and an anode, and a plurality of grids positioned between the cathode and anode and including a signal grid, screen grid and suppressor grid, said cathode being provided with at least two leads extending between the cathode and the exterior of the envelope, mica spacers at opposite ends of the mount for spacing the cathode, anode and grids, alternate mica spacers and conducting plates adjacent one end of said mount, one of said conducting plates being electrically connected to the screen grid and another of said plates being electrically connected to the cathode, and a third plate being connected to the suppressor grid, the plate connected to said cathode being between the plates connected to the suppressor grid and the screen grid.

4. An electron discharge device having an envelope containing a cathode and an anode, and a plurality of grids positioned between the cathode and anode and including a signal grid, screen grid and suppressor grid, mica spacers at opposite ends of the mount for spacing the cathode, anode and grids, alternate mica spacers and conducting plates adjacent each end of said mount, one of said plates at each end being electrically connected to the screen grid and another of said plates at each end being electrically connected to the cathode, and a third plate at each end being connected to the suppressor grid, the plates connected to said cathode being between the plates connected to the suppressor grid and the screen grid.

5. An electron discharge device having an

envelope containing a mount including a cathode and an anode, and a plurality of grid electrodes positioned between the cathode and anode and comprising a signal grid, screen grid and suppressor grid, mica spacers mounted at opposite ends of said mount for spacing the anode, cathode and grid electrodes, a conducting plate extending across one end of said mount and electrically connected to said cathode, a pair of semi-circular conducting plates positioned adjacent said first conducting plate and insulated therefrom by means of an insulating spacer, and an electrical connection between the suppressor grid and one of said semi-circular plates, and an electrical connection between the screen grid and the other semi-circular plate.

6. An electron discharge device for use at high frequencies and having a cathode and anode, and a control grid, and a screen grid between the control grid and anode, a plurality of leads connected to said cathode, one of said leads being adapted to be connected to an input circuit and a by-passing condenser connected between the screen grid and another of said leads.

7. An electron discharge device for use at high frequencies and having a cathode and anode, and a control grid positioned between the cathode and anode, and a plurality of other grids positioned between the control grid and the anode, a plurality of leads connected to said cathode, one of said leads being adapted to be connected to an input circuit and another of said leads being adapted to be connected to an output circuit, and a condenser directly connected between the cathode and one of said other grids between the control grid and anode.

BERNARD SALZBERG.
